United States Patent Office

Des. 203,884
Patented Feb. 22, 1966

203,884

BOTTLE

William F. Wood, 109 La Paloma Ave., Alhambra, Calif.

Filed Feb. 9, 1965, Ser. No. 83,750

Term of patent 14 years

(Cl. D58—6)

FIG. 1 is a side elevation of a bottle showing my new design;

FIG. 2 is a top plan view thereof;

FIG. 3 is an end elevation thereof; and

FIG. 4 is a plan section taken along line 4—4 of FIG. 1.

The side and end not shown are similar to the side and end illustrated.

I claim:

The ornamental design for a bottle as shown and described.
